ASH TRAY SUPPORT

Chester A. Huettenrauch, Chicago, Ill.

Application June 1, 1939, Serial No. 276,877

2 Claims. (Cl. 248—311)

This invention relates to an improved ash tray support particularly adapted for demountably supporting an ash tray by attachment to the underside of a chair arm or to the underside 5 of a desk or table, and is especially designed for use on the arms of barber chairs.

More particularly, it is an aim of this invention to provide an improved bracket adapted to be secured to the underside of a barber's or cosmetician's chair and a stem having means for detachably securing it to an ash tray and loosely mounted in one end of the bracket for removably supporting the ash tray thereon.

Other objects and advantages of the invention will hereinafter become more fully apparent from the following description of the drawing, which illustrates a preferred embodiment thereof, and wherein:

Figure 1 is a side elevational view, partly in section, showing the support in an operative position,

Figure 2 is a bottom plan view partly in section of the same, and

Figure 3 is an end view in elevation of the bracket.

Referring more particularly to the drawing, wherein like reference characters designate like or corresponding parts throughout the different views, 10 designates a chair arm support and 11 an arm mounted thereon. These parts are of conventional construction of the type generally employed on barbers' chairs, and are shown merely to illustrate an application of the invention, designated generally 12, which will herein-after be described.

The support 12 includes a tubular bracket, designated generally 13, one end of which is flattened to form the bar 14 which is provided adjacent its free end with the offset portion 15 adapted to receive the member 10 when the end 14 is positioned against the underside of the chair arm 11. The end or bar 14 is provided with the openings 16 on either side of the offset portion 15 to receive the screw fastenings 17 which are secured to the arm 11 for mounting the bracket 13 on the underside thereof. The opposite tubular end 18 of the bracket 13 extends upwardly from one end of the bar 14 in spaced apart relationship to one side of the arm 11, as best seen in Figure 1.

A cup shaped ash tray 19 is provided with a tapered bottom having a central opening 20 to receive the threaded bolt 21. The shank of the bolt 21 extends downwardly from the bottom of

the ash tray 19 and is provided with a nut 22 which is adapted to be tightened to clamp the center of the bottom portion of the tray 19 between the head of the bolt 21 and the nut 22. The exposed end of the shank 21 extends downwardly into the tubular upwardly extending end 18 of the bracket 13 with the nut 22 forming a shoulder for engaging the free end of the tubular portion 18 for supporting the tray 19.

From the foregoing it will be seen, that the bolt 21 may be readily applied to or removed from the tubular portion 18 to apply or remove the ash tray 19 thus providing a support whereby an ash receiver may be readily mounted on a chair arm or on the underside of the edge of a tray or table 15 and in which the ash tray will be held against casual removal.

Various modifications and changes are contemplated and may be resorted to and the right is reserved to make such variations as fall within the spirit and scope of the invention as herein-after defined by the appended claims.

I claim as my invention:

1. An ash tray support comprising a bracket, one end of said bracket being adapted to be secured to the underside of a chair arm, said bracket having an opposite end offset outwardly from the arm and projecting upwardly, said last mentioned end being tubular, and a stem having locking means for detachably securing it to the bottom of an ash tray, said stem being loosely mounted in the tubular end of said bracket for removably supporting the ash tray thereon, and said locking means having a flat bottom for engaging the tubular end of the bracket to retain the tray in an upright position.

2. An ash tray comprising a bracket having an end shaped to fit the underside of a chair arm and detachably secured thereto, the opposite upwardly projecting end of said bracket being tubular and being offset outwardly relatively to the chair arm, a cup shaped tray having a dished bottom provided with a central opening, a headed bolt extending downwardly through the opening, and a nut on said bolt for clamping the head in the bottom of the tray to close the opening, the exposed end of the bolt forming a stem for engaging the tubular end of the bracket for removably mounting the tray thereon, the bottom of the nut forming a flat supporting surface for engaging the tubular end of the bracket.

CHESTER A. HUETTENRAUCH.
